Fig. 1.

FIG. 2.

Fig. 3.

UNITED STATES PATENT OFFICE.

HENRY J. BARNETT, OF GREEN RIDGE, MISSOURI.

LEVEL.

Application filed January 14, 1925. Serial No. 2,332.

This invention relates to a leveling instrument.

It is aimed to provide a novel construction adapted for operation by a weight and designed to be read from opposite sides.

Another object is to provide a novel construction wherein the indicator and its pendulum are mounted in a novel manner by a casing whose parts coact with the stop or body of the level to secure the various component parts of the instrument together.

Additional objects and advantages will become apparent from a consideration of the description following, taken in connection with the accompanying drawings illustrating an operative embodiment.

In said drawings:—

Figure 1 is a view of the instrument in side elevation.

20 Figure 2 is a sectional view taken on the line 2—2 of Figure 1.

Figure 3 is a fragmentary view mostly in side elevation with the dial and associated parts at one side removed.

25 Like reference characters designate like or similar parts in the different views.

In carrying out the invention, a stock or body 10, of wood, metal or any other appropriate material is provided with an opening, for instance, centrally thereof to accommodate the working parts. Disposed within the said opening is a casing 11 comprising sections 12, of substantially similar shape and removably telescoped with each other as shown. These sections have flat disks 13 constituting their side walls and exteriorly having delineations or calibrations 14 to indicate angles. The outer edge portions of the disks or dials 13 extend beyond the curved or telescoping walls 15, which complete the sections 12, as indicated at 16. Said portions 16 overlap the opposite sides of a rib 17 forming part of the stop and extending inwardly of the remainder of the opening. The sections 12 are secured together and to the stock by means of detachable bolts or other fastenings 18 which pass through the portions 16 and rib 17.

50 Journaled in the disk 13 in any suitable manner, as on ballbearings, or by means of jewel bearings, or otherwise, is a spindle 19 from which a pendulum or weight 20 of any suitable size, shape or material is suspended by an arm 21 rigid with the spindle and with

the pendulum. The spindle extends beyond the arm 21 in order to pass through and be journaled in the disks 13 and beyond such disks have indicators or pointers 22 screw-threaded or otherwise detachably connected thereto. Washers 25 may be interposed between the disks 13 and arm 21, and mounted on the spindle 19.

The edge portion about the opening aforesaid, is recessed as at 26 on each side of the stock to form a seat for transparent panels 27 of glass, celluloid or the like. Said panels are removably secured in place by metallic rings 28 overlapping the same and detachably connected to the stock as by means of screws 29 passing through the rings and into the stock.

In use, the stock is placed in engagement with the desired surface and according to the angularity of the stock, the pendulum 20 will move the spindle 19 as such pendulum seeks the vertical. Since the pointers or indicators 22 move with the spindle 19, they indicate the level or angularity of the said surface in combination with the calibrations 14. These indications may be observed from opposite sides of the instrument.

Various changes may be resorted to provided they fall within the spirit and scope of the invention.

I claim:

A leveling instrument comprising a stock having an opening, a rib on the stock extending into the opening, a casing having sections, each section having a flat wall constituting a dial and overlapping a side of said rib, each section having an annular wall extending inwardly from the dials, said annular walls being in telescopic relation and occupying said opening, the outer portions of said dials and rib having registrable openings to aid in correctly positioning the dials with respect to each other and with respect to the stock, removable fastenings passing through the openings in said dials and said rib, a spindle removably journaled in said dials having washers thereon abutting the inner surface of each dial, an arm extending from said spindle intermediate the dials, a pendulum carried by said arm, pointers detachably secured to said spindle at the ends thereof and movable over said dials.

In testimony whereof I affix my signature.
HENRY J. BARNETT.
